UNITED STATES PATENT OFFICE

ROBERT E. HOLLETT, OF DES MOINES, IOWA, ASSIGNOR, BY MESNE ASSIGNMENTS, TO
PORTABLE MILLING COMPANY, OF DES MOINES, IOWA, A CORPORATION OF IOWA

DESIGN FOR A PORTABLE GRINDER

Application filed September 22, 1930. Serial No. 37,037. Term of patent 14 years.

To all whom it may concern:

Be it known that I, ROBERT E. HOLLETT, a citizen of the United States, and a resident of Des Moines, in the county of Polk and State of Iowa, have invented a certain new, original, and ornamental Design for a Portable Grinder, of which the following is a specification, reference being had to the accompanying drawing, forming part thereof.

Figure 1 is a plan elevation of a portable grinder embodying my design.

Figure 2 is a rear elevation of the same,

the centrifugal separator being shown broken away.

Figure 3 is an elevation of one side of the portable grinder; and

Figure 4 is an elevation of the opposite side thereof.

I claim:

The ornamental design for a portable grinder as shown.

Des Moines, Iowa, September 8, 1930.

ROBERT E. HOLLETT.
